(57) **CLAIM**

The ornamental design for a combined breeder box and panel assembly, as shown and described.

DESCRIPTION

FIG. 1 is a perspective view of a combined animal enclosure and breeder box assembly shown according to the present design;

FIG. 2 is a front end view thereof;

FIG. 3 is a rear end view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines in the figures illustrate portions of the combined animal enclosure and breeder box assembly that form no part of the claimed design.

1 Claim, 6 Drawing Sheets
